JOHANN KOZICZ, OF VIENNA, AUSTRIA

METHOD OF AND APPARATUS FOR MAKING METAL TUBES

Application filed January 10, 1927, Serial No. 160,181, and in Austria January 16, 1926.

My invention relates to an improved method of and apparatus for bending metal strips between pairs of rolls.

Arrangements for carrying out this method are already known, in which the cross-sectional shapes of the rolls are such, that the metal strip is pressed between two rolls along its entire cross-sectional area, so that it is necessary to increase the pressure of the roll 10 and to lubricate the strip, while at the same time the material is hardened, which is not desirable as it is detrimental to a uniform shaping and employment of the metal tube. One of the rolls of one or more of the final 15 pairs of rolls is formed with a central circumferential flange serving to prevent the edges of the strip from being forced together.

According to the present invention, the metal strip is subjected to a pressure at both 20 sides in the vicinity of the longitudinal edges only between a series of pairs of rolls of gradually varying consecutive cross-sectional shapes, the distance between the top roll and the bottom roll of each pair of rolls, except 25 those at or near the outlet end of the series being smaller at the outer edges of the profiles of the rolls than in the middle thereof.

Because the metal strip rests only against the top roll and is firmly pressed solely at 30 the edges, while its middle portion lies hollow, any excessive generation of heat is prevented, so that the lubrication of the strip and the cooperating faces of the rolls can be dispensed with. Further, in the case of rusty 35 or scaly sheet-metal being used, the rust or scale dropping off during the bending operation may readily drop into the hollow space remaining between the two cooperating rolls, so that the rust or scale cannot be pressed into 40 the roll. In the old methods this rust or scale is pressed into the surface of the rolls, and consequently the latter quickly wear off and become untrue, so that the metal strips are damaged and deformed during the passage 45 between the rolls. This drawback is still more increased in the event of lubricated rolls, because rust or scale adheres to a greater extent.

By arranging the rolls according to the 50 present invention one can employ not only

raw sheet metal, but also nickel-plated or like sheet metal, which passes out of the last pair of rolls quite dry and without requiring any finishing work, so that the cross-sectional area of the tube to be made is quite immaterial. Particularly square tubes can be rolled over the edge by this method. A further advantage consists in this that the pairs of rolls at or near the inlet end of the series will serve for the production of a number 55 (four to five) of different profiles, for the completion of which it is necessary only to exchange from time to time the corresponding end or last pair of rolls, while the other rolls remain the same.

In the drawings:—

Figs. 1 and 2 illustrate diagrammatically an apparatus in sectional elevation and plan view respectively for carrying out the method according to the present invention.

Figs. 3, 4, 5 and 6 illustrate four successive pairs of rolls.

As shown in Figs. 1 and 2, the apparatus comprises two double walls 1 and 2 between which are arranged the drawing-in rollers E and F, the profiling or forming rolls A, B, C and D and the guide-rolls 9 and 10 for the band-iron or the metal strip. The two walls 1 and 2 are divided into sections, in which are arranged the roller-bearings 4 and 5 of the top- and bottom rolls, the bearing of each bottom roll resting on a support 6. The individual sections are connected with one another by longitudinally extending bars 19. The roller-bearings 4 and 5 and the supports 6 are provided with two vertical grooves, by means of which they are guided on the two plates of the double walls 1 and 2. The height of the bottom roll is determined by the height of the support 6, while the top roll 70 can be adjusted by means of set screws 8. Suitably shaped guide-rolls 9 and 10 are arranged in any convenient manner intermediate the individual profiling or shaping rolls, while the drawing-in rollers E and F are 75 mounted on a bearing 11, secured to the two double walls 1 and 2. The rolls are rotated by means of toothed bevel-wheels 14, which mesh with bevel-wheels 13, secured on a common drive shaft 12. In the illustrated em- 80

bodiment, the top roll of each pair of rolls is rotated by the gear and is provided with a toothed wheel 15, which meshes with a toothed wheel secured to the shaft of the corresponding bottom roll, so that the top rolls and the bottom rolls are rotated in opposite directions.

As shown in Figs. 3 to 6, the profile or cross-sectional shape of each pair of rolls A, B, C and D is such, that the distance at the outer rim or edge p is smaller than at the middle m so that, provided the band-iron or metal strip is of a uniform thickness, the latter is pressed at the outer rim or edge only between the two rolls, while the remaining portion of the said strip solely rests against the top roll and does not contact with the bottom roll. In order to prevent a lateral displacement between the two rolls and to accurately adjust the profile or cross-sectional shape, the top rolls are provided with a collar b at both ends, which collar engages a corresponding circumferential groove c of the bottom roll. In order to prevent a screw shaped tube-seam, the top roll D of the pair of rolls, through which the tube passes immediately before the finishing of the profile, is equipped with a central disc D', which enters the tube-seam and moves in the same during the feed of the tube. Preferably, the guide-roll 10, lying behind the same, is provided with a similar disc, in order to prevent the tube from being subjected to torsion behind the presser roll D.

The machine operates in the following manner:-

The metal strip is passed by way of the drawing-in rolls F to the first pair of shaping rolls A, is grasped by the rotating top and bottom rolls and is automatically fed to the next pair of rolls and so on, until the shaping is finished by a roll disposed behind the roll D. The tube is smoothed and exactly shaped by a subsequent roll, the tube thus leaving the machine in a soft and dry condition and provided with a seam. If necessary, a welding device may be disposed behind the last roll, to close the entire seam in one operation.

The central-disc D' of the top roll D projects through the seam of the tube and directly operates on the metal strip resting upon the bottom roll, so that this disc not only guides the seam of the tube in a straight line, but also serves as a means for holding down the metal strip, disposed in the bottom roll.

As the metal strip is subjected to a pressure only in the vicinity of its edges, the shaping is, at first, carried out by a simple bending operation about the top roll and therefore any excessive generation of heat and undesirable strains are prevented.

Of course, instead of circular cross-sectional shapes also tubes of oval, right-angled or square shape may be made, whereby also

in these cases the guide- and retaining discs D' of the corresponding shaping rolls prevent any torsion in the produced tubular prism and safeguard the accurate shape of the tube.

Also a number of tracks of rolls may be arranged side by side in a single frame, so that tubes of different diameters may be bent simultaneously in a single operation.

I claim-

1. The method of bending a metal strip comprising passing said strip between successive pairs of rolls of gradually differing cross-section so as to subject the metal strip to pressure along its longitudinal edges only, and maintaining the other portion of the metal strip out of contact with the bottom roll of each pair of rolls.

2. An apparatus for bending a metal strip comprising successively arranged pairs of superposed shaping rolls of gradually differing cross-section, the distance between the cooperating surfaces of said rolls at their outer edges being smaller than in their center so as to prevent contact of the metal strip with the bottom roll, means for rotating said rolls, and disk-shaped guide elements intermediate said pairs of rolls.

3. In apparatus for bending a strip into tubular form, a pair of cooperating rolls between which the strip is adapted to be passed, one of said rolls having a groove and the other having a cooperating projection extending into said groove, the contours of the groove and the projection being such that when the rolls are in contact with the strip to either side of said groove and said projection, a space exists between the strip and the bottom of the groove in the first mentioned roll.

In testimony whereof I affix my signature
JOHANN KOZICZ.
